APPARATUS FOR DELIVERING MEASURED QUANTITIES OF MATERIAL

Johan Gunnar Nilsson, Appelviken, Sweden, assignor to Areenco Aktiebolag, Stockholm, Sweden, a Swedish joint-stock company

Application April 26, 1946, Serial No. 665,169
In Sweden April 28, 1945

3 Claims. (Cl. 222—380)

1

This invention relates to apparatus for delivering measured quantities of more or less viscous or semi-liquid material. More particularly the invention relates to apparatus of such kind having a delivery channel and having a valve provided with a passage adapted to periodically constitute a downwardly directed outlet end of said delivery channel. Apparatus of this kind are well adapted for the delivery of certain materials, but they are affected with certain drawbacks when adapted to deliver certain other materials such as jellies, preserves, etc. which are sluggish in flow and have a tendency to adhere to the wall of the housing of said valve and form strings suspended from said housing. It is an object of the invention to remove said drawbacks.

The accompanying drawing shows, by way of example, an embodiment of the invention.

Fig. 1 is a vertical sectional view of an apparatus embodying the invention;

Fig. 2 is a sectional view taken on the line II—II of Fig. 1; and

Fig. 3 is a view from below of the parts shown in Fig. 2.

Referring to the drawing, a vertical pipe 1 is formed integral with a pump housing 16 in which is rotatably journaled a pump cylinder 2. A piston 3 adapted to reciprocate in the cylinder 2 is pivotally connected to a connecting rod 4. The connecting rod 4 is also pivoted to a double-armed lever 5 which is secured to a rotatably journaled shaft 6. The free end of the lever carries a roller 32 which is pressed by a spring 33 against a cam disc 7 secured to a rotary driving shaft 8.

The cylinder 2 is formed integrally with a toothed flange 17 which meshes with a toothed rack 18 which constitutes the end of a rod 38. The lower, forked end 39 of the rod 38 carries a roller 19 which rides on a cam disc 20 secured to the shaft 8. The cylinder 2 has an inlet opening 22 and an outlet opening 23 for material.

The lower end of the pipe 1 is formed integral with a substantially cylindrical valve housing 9 the bottom portion of which is cut out to form a slot 34 having sharp scraper edges 10a and 10b from which the surfaces 35 extend obliquely upwardly. The valve housing 9 is provided with a cylindrical bore in which is located a cylindrical plug 11 which is rotatable in said bore. The valve plug 11 has a passage 12 extending transversely therethrough. As shown in Fig. 3 the scraper edges 10a and 10b of the valve housing coincide substantially with the side edges 25 of the mouth 13 of the passage 12 when the valve is open. At

such a position of the valve, the surfaces 35 of the housing 9 are in close proximity to the side edges 25 of the mouth 13 of the passage 12.

When the valve is closed, the surfaces 35 of the housing 9 are in close proximity to the edges 10a and 10b of the slot 34.

When the valve is closed, the surfaces 35 of the housing 9 are in close proximity to the edges 10a and 10b of the slot 34.

When the valve is closed, the surfaces 35 of the housing 9 are in close proximity to the edges 10a and 10b of the slot 34.

When the valve is closed, the surfaces 35 of the housing 9 are in close proximity to the edges 10a and 10b of the slot 34.

When the valve is closed, the surfaces 35 of the housing 9 are in close proximity to the edges 10a and 10b of the slot 34.

When the valve is closed, the surfaces 35 of the housing 9 are in close proximity to the edges 10a and 10b of the slot 34.

When the valve is closed, the surfaces 35 of the housing 9 are in close proximity to the edges 10a and 10b of the slot 34.

When the valve is closed, the surfaces 35 of the housing 9 are in close proximity to the edges 10a and 10b of the slot 34.

When the valve is closed, the surfaces 35 of the housing 9 are in close proximity to the edges 10a and 10b of the slot 34.

When the valve is closed, the surfaces 35 of the housing 9 are in close proximity to the edges 10a and 10b of the slot 34.

When the valve is closed, the surfaces 35 of the housing 9 are in close proximity to the edges 10a and 10b of the slot 34.

When the valve is closed, the surfaces 35 of the housing 9 are in close proximity to the edges 10a and 10b of the slot 34.

When the valve is closed, the surfaces 35 of the housing 9 are in close proximity to the edges 10a and 10b of the slot 34.

When the valve is closed, the surfaces 35 of the housing 9 are in close proximity to the edges 10a and 10b of the slot 34.

When the valve is closed, the surfaces 35 of the housing 9 are in close proximity to the edges 10a and 10b of the slot 34.

When the valve is closed, the surfaces 35 of the housing 9 are in close proximity to the edges 10a and 10b of the slot 34.

When the valve is closed, the surfaces 35 of the housing 9 are in close proximity to the edges 10a and 10b of the slot 34.

When the valve is closed, the surfaces 35 of the housing 9 are in close proximity to the edges 10a and 10b of the slot 34.

When the valve is closed, the surfaces 35 of the housing 9 are in close proximity to the edges 10a and 10b of the slot 34.

When the valve is closed, the surfaces 35 of the housing 9 are in close proximity to the edges 10a and 10b of the slot 34.

When the valve is closed, the surfaces 35 of the housing 9 are in close proximity to the edges 10a and 10b of the slot 34.

When the valve is closed, the surfaces 35 of the housing 9 are in close proximity to the edges 10a and 10b of the slot 34.

When the valve is closed, the surfaces 35 of the housing 9 are in close proximity to the edges 10a and 10b of the slot 34.

When the valve is closed, the surfaces 35 of the housing 9 are in close proximity to the edges 10a and 10b of the slot 34.

When the valve is closed, the surfaces 35 of the housing 9 are in close proximity to the edges 10a and 10b of the slot 34.

I claim:

1. In an apparatus for delivering measured quantities of material, a delivery channel, means for periodically forcing the material down through said channel, a valve having a plug pro-

vided with a passage adapted to periodically constitute a downwardly directed free outlet end of said delivery channel, said valve having a housing for said plug provided with an opening having an obliquely downwardly directed cutting edge engaging said plug and being adapted to substantially coincide with one edge of said outlet end when said plug is in open position and also forming a bottom edge of an obliquely upwardly extending surface of said housing, and means for periodically opening and closing said valve plug by moving said outlet end of said passage past said cutting edge.

2. In an apparatus for delivering measured quantities of material, a delivery channel, means for periodically forcing the material down through said channel, a valve having a plug provided with a passage adapted to periodically constitute a downwardly directed free outlet end of said delivery channel and having a cutting edge, said valve having a housing for said plug provided with an opening having a surface extending obliquely downwardly toward said plug and having at its bottom end a downwardly directed cutting edge engaging said plug and being adapted to extend close by said edge of said outlet end when said plug is in open position, and means for periodically opening and closing said valve plug by moving said outlet end of said passage past said cutting edge of said opening.

3. In an apparatus for delivering measured quantities of material, a delivery channel, means for periodically forcing the material down through

5 said channel, a valve having a plug provided with a passage adapted to periodically constitute a downwardly directed free outlet end of said delivery channel, said valve having a housing for said plug provided with an opening having a pair of downwardly directed cutting edges engaging and extending longitudinally of said plug, said outlet end of said passage having a pair of oppositely disposed cutting edges adapted to substantially coincide with said cutting edges of said opening when said plug is in open position and being interconnected by curved cutting edges, and means for periodically opening and closing said valve plug by rotating said plug to move said oppositely disposed cutting edges and said curved cutting edges past one of said cutting edges of said housing.

JOHAN GUNNAR NILSSON.
